COIN SORTING MACHINE

Edward B. Paul, Wyoming, Ohio, assignor to
Josey P. Stacey, Wyoming, Ohio

Application April 2, 1935, Serial No. 14,311

8 Claims. (Cl. 133—3)

My invention relates to coin separating and counting devices, and is concerned more particularly with a machine for the counting of coins or tokens in large quantities and the presentation of 5 a segregated total for each of the denominational values of the coins. My invention provides for a rapid count and separation of the various coins into groups according to their value, and for the separation and final ejection of defective, bent 10 and vagrant coins.

Means are provided for a power drive whereby a very rapid count is made possible. There is provided a coin separating device in the form of a power driven coin conveyor chain, having open 15 links for carrying the various coin values; a still further provision being for the quick release of the coins from the conveyor chain and the rapid passing of the coins to the count devices.

A further feature is the provision of a separate 20 count mechanism for each coin value, these mechanisms registering a coin only when that coin has been separated from the other coins and has been passed through its appropriate registering device.

25 A further feature is a totaling unit count mechanism which, at the end of the sorting operations, will give a visual total in dollars and cents of each denominational coin value; and the mechanism being further capable of a rapid set back to zero 30 on all values at one operation.

A still further feature is a novel power driven coin feeder designed to provide a continuous uniform feed of the coins to the segregating coin conveyor chain.

35 Still further features of my invention will be disclosed as the description proceeds, and will be made the subject matter of some of the more specific claims.

In the drawings:

40 Figure 1 is a perspective view of the complete coin separating and counting machine.

Figure 2 is a plan view of the coin receiving plate with the coin conveyor chain in position, some of the overlying mechanisms being omitted 45 from the view.

Figure 3 is a plan view of the coin receiving plate, with the coin conveyor chain omitted.

Figure 34 is a detail view of a bag clip.

Figure 35 is a plan view of one link showing a half dollar resting therein.

Figure 36 is a cross sectional view taken on the line 36—36 of Figure 35.

Figure 37 is a view similar to Figure 35 showing two ten cent pieces resting in the coin pocket, and

Figure 38 is a cross sectional view of the same taken on the line 38—38 of Figure 37.

Proceeding now with the description of the mechanisms:

35 A frame 1 supports a base plate 2, and forms the main support for the mechanisms of the counter. Secured to the plate 2 are frame members 3 which support a coin plate 4, the coin plate being supported at an approximate angle of 40 forty-five degrees.

Depending from the base plate 2 are the bearing brackets 6 carrying a shaft 5, this shaft having secured to it a combined pulley and flywheel 7. One end of the shaft 5 has secured thereon a bevel gear 8. Projecting downward near the left end of the coin plate 4, are the bearing brackets 10 and 11. Intermediate of the bearing brackets 10 and 11, at the central line of coin plate 4, is a U-shaped bracket 12, which furnishes bearing support for a series of shafts, as will be later described.

Coin plate construction

The coin plate 4 is formed with semi-circular ends, having at the center of the radii of the ends, bearings for driving discs 13 and 14. The driving disc 13 has a shaft 15 extending downward through a roller bearing 16 carried by the bearing support 12. Secured to the shaft 15 is a bevel gear 17 which is driven by a bevel pinion 18, mounted on a shaft 19, carried in bearings in the brackets 11 and 12. The shaft 19 has secured to it a bevel gear 9, which is in driving relationship with the power pinion 8. The disc 13 is formed with a flat central portion, sloping to a thin edge, this thin edge having an undercut portion in which are located a series of driving lugs 29 equally spaced apart around the disc 13.

The coin plate 4 has an upwardly extending wall portion 20 around a portion of its periphery, this wall portion extending from a point slightly above the center line at the right hand end of the coin plate 4 (Fig. 2), to a point at the left end, ending at a point near the juncture 75 of the left hand curve with the upper straight

side. The major portion of this wall has an undercut groove 21 at its juncture with the coin plate 4, the function of which will be disclosed later on in the description. It is to be noted that the right hand end of the wall portion is 5 free of the coin plate and is curved inward.

Passing around the periphery of the discs 13 and 14 is a coin conveyor chain composed of separate link members 22. Each of these link members has a hole 22a for the reception of 10 coins, one side of this hole being chamfered at 22b to prevent the carrying, by the link, of more than one coin. The circular hole of the coin link is deformed by a straight portion 23, for the purpose of preventing the entrance of more 15 than one of the coins of smaller denomination at a time, while still permitting more than the major portion of a coin of the largest denominational value to enter and be carried by the coin link.

Each coin link has an inner and an outer 20 curved and rabbeted edge 24—25, the curvatures being equal to that of the end portions of the coin plate 4. The outer rabbeted portions 24 of the coin links 22 fit into the grooves 21 in the coin plate wall 20, while the inner rabbeted portions 25 fit under the undercut portions 26 of the 25 discs 13 and 14 in a groove 27, cut in the edge of the thicker center portion 28 of the coin plate 4. The portion 28 is thicker than the remainder of the plate because of the fact that the plate is 30 cut away to accommodate the discs 13 and 14 and the chain.

The coin links 22 are formed into an endless coin conveyor chain 30, as seen in Figure 2, passing around the discs 13 and 14, and held in a flat 35 position on the coin plate 4 by the engagement of the rabbeted portions of the chain links 22 with the grooves 21 and 27 and the undercut portions 26. The separate coin links 22 are joined together into an endless chain by the 40 small links 30a, which are secured to the coin links by pins 31 passing through holes 32 in the coin links. Since these links 30a form projections on the undersides of the links 22, a groove 32a (Figs. 3 and 22) is provided for the passage 45 of these links around the coin plate 4.

An inspection of Figure 4 reveals that when power is applied from the gearing previously described to the gear 17, the disc 13 is rotated, and by means of lugs 29 entering notches 28a, drives 50 the coin conveyor chain and disc 14 at a degree of speed suitable for the operation of the mechanisms of the machine.

Supported by a bracket 32 (Figs. 4, 5 and 13) at the right hand end of the coin plate 4, is a coin 55 hopper 33, having a grooved flange 34 in which the coin discharge tube 35 is adapted to rotate, the opposite end of the tube revolving in a bearing in a bracket 36 supported by the central portion of the coin plate 4. Keyed to the coin tube 35 at the right, is a large bevel gear 37, this gear 37 being in driving relationship with a bevel pinion 38, carried by the disc 14. Internally disposed within coin tube 35 is a conveyor screw 39, to provide a controlled feed of the coins to 65 the coin plate 4. As the coins of mixed denominational value are placed in hopper 33, they pass into and drop from the coin discharge tube to the coin plate 4, and they at once, due to the angle of inclination of the coin plate, roll to the lower- 70 most portion of the plate.

In order that the coins shall not lodge against the side wall 20 in a standing or edge position, there is provided a flexible deflector member 40, which is hinged at 41, and having its opposite 75

end free to rise and fall, guided by a pin 42 traveling in a slot 43 in the side wall 20. The angle of the deflector member is such that the coins striking it are deflected into flat position 5 on the coin plate 4. A second coin deflector 44 (Figs. 3 and 17) is provided to prevent the bunching or piling of the coins at the left end curve of the wall 20. The deflector 44 is free to rise and fall, guided by pins 45 which travel in slots 10 46 in the wall 20. The flexible feature of the deflector serves to break up and dissipate any grouping of the coins, and to prevent breakage 15 of the coin conveyor chain.

As the coin conveyor chain 30 travels around 15 the coin plate 4, the coins drop into the holes 22a of the links 22, and are carried around to the high side of the coin plate for further disposal. The speed of the coin conveyor chain is such that at times there is a tendency for a second 20 coin to adhere to and travel with a coin seated in the links 22. To prevent this, there is provided a flexible deflector dam 47 (Figs. 3 and 14) pivoted at 48 and held lightly in contact with the surface of the coin conveyor chain by a 25 spring 49. A stop 50 is provided to allow the dam 47 to rise only far enough to permit a partially seated or a heavy coin to pass under it, while still deflecting downward any superfluous coins.

It will be observed that the fifty cent piece is 30 not permitted to lie flat in the coin pocket on account of the deformation 23. Yet, as will be clear from a consideration of Figure 35 the half dollar is well enough seated in the coin pocket so that as the coin chain travels upwardly as in 35 Figure 36, the deflector dam 47 will simply ride over it. It will be understood from a consideration of Figure 35 that there is some contact between the edge of the coin and the circular portion of the edge of the hole in the link 22, the 40 rear half of the link considering the direction of motion of the link which is to the right in Figure 35 or upward in Figure 36.

Passing now to a consideration of Figures 37 and 38, it will be observed that the edge of the 45 free ten cent piece will be contacted by the deflector dam 47 and since the inner edge of the chamfer 22b is lower than the top of the lower ten cent piece the free ten cent piece will simply be slid off the link. This can be accomplished 50 without the deflector dam having to rise against the tension spring 49. If, for example, the free ten cent piece were not lying flat upon the lower ten cent piece but it were tilted, it is clear that it would have to be tilted at a steep angle. Thus, 55 it might cause the deflector dam to rise, but generally speaking, the deflector dam will not rise where two small coins are found one upon the other. The provision for resilience in the member 47 is to permit the passage of a large coin as, 60 for example, the fifty cent piece which cannot under any circumstances lie flat in the coin pocket.

Assume now that for example a smaller coin is resting on top of the fifty cent piece and assume 65 that the coins have some sticky material upon them, then the deflector dam may bear against the stop 50 so as to positively remove the free coin. Likewise if two smaller coins were stuck together the free coin would be positively re- 70 moved.

It will be clear that it does not take much to remove the free coin from the lower coin because of the angle at which the coin plate is set. In actual practice, it is quite rare that a second coin 75 will be carried upon the relatively steep incline

while resting on top of a coin which is properly seated. The deflector dam 47, however, is a safety provision to specially prevent a second coin which may have stuck to a seated coin from being carried through to the counting machine. 5

The coin plate 4 has at the top or high side, and directly under the path of the coin conveyor chain, a long, graduated slot 51 (Figs. 2, 3, and 15), one side of this slot having a shallow stepped formation 52, seen best in Figure 2. The first and 10 lowermost step ends at 53; the next or second step ends at 54, the third step ends at 55, the fourth step ends at 56, the fifth step ends at 56a, and the balance of the slot 51 is of a width equal to that of the holes 22a in the coin conveyor chain. 15 Note that a portion of the coin plate 4 projects beyond the edges of the coin holes 22a as at 57 (Figure 2), thus forming a ledge portion. The purpose of the stepped formation of slot 51 and the ledge 57 will now be set forth. 20

As the coins are picked up one by one and carried around by the coin conveyor chain, the inclined position of the coin plate 4, carrying the coin conveyor chain, causes the coins carried by it to seek the lowest position in the holes 22a of 25 the links 22. To insure that these coins are correctly seated in a flat position in the links, there is provided a seating disc 58 (Fig. 3), driven by a gear train 59, receiving its driving power from gear 17 (Fig. 4) through the pinion gear 60, the 30 shaft 61, the bevel gears 62, the shaft 63, the bevel gears 64, and the shaft 65 on which is secured the gears of gear train 59. The disc 58 has around its periphery, at four equidistant points, the spring plungers 66, having exteriorly 35 conical end portions. The timing of disc 58 is such that a plunger makes contact with each coin as it passes the position of the disc 58, thus positively seating the coins in the coin links 22.

As the coin conveyor chain moves to the right, 40 the coins are prevented from dropping out of the links 22 through the slot 51, by the fact that their edges rest on the stepped portions 52 and on the ledge 57.

Presume now a dime to be the first coin to reach 45 the ledge ending at 53. This dime is carried to the right by the coin conveyor chain 30, its edges resting on the ledges 53 and 57 until the end of ledge 53 is reached. Here the upper edge is set free, and the coin tilts downward and drops from 50 the ledge 57 into a coin guide, and is passed to the counting mechanisms as will be described later.

If, for any reason, the dime should fail to drop, it is forced to do so by the plunger 67a in the disc 67. This disc is in all respects similar to the 55 disc 58, previously described, and is driven from the shaft 65 by the bevel gears 68 and the shaft 69, and presents a plunger to each coin passing under its periphery. The discs 67b are in all respects similar to the disc 67, and perform like 60 functions for one cent, five cent and twenty-five cent coins.

Similarly, the penny is discharged when it reaches the end of the ledge 54, the five cent piece when it reaches the end of the ledge 55, the 65 quarter when it reaches the end of the ledge 56, and the half-dollar drops by gravity when it reaches the end of the ledge 70.

Each coin except the half-dollar is caught as 70 it drops, by a guide chute 71 (Figs. 2 and 4), and is guided thereby to the count recording mechanisms, which will presently be described. The half-dollar has a special count recording mechanism which will be described later. 75

The counting devices

All the coins deposited in the coin sacks or other receiving means, must have an accurate count. Since the coins are deposited in the coin sacks so rapidly, it becomes impossible to get an accurate count by having the dropping coins operate the count mechanisms. The count, therefore, is made after the coins are passed through count recording devices and before they are deposited in the coin receiving means.

Attention is now called to Figure 4. Note that to the left of the inclined coin plate 4, is disposed a shaft and mechanisms supported by upright brackets. These mechanisms are best seen in Figures 6 and 7. Proceeding now with the description of the construction, the brackets 72 and 73 support a shaft 74. Mounted at one end of the shaft 74 is a gear 75, which receives its driving power from the gear 17 through the bevel gear 76, the gear 77, and the intermediate gear 78, the shaft 74 being constantly driven when the coin sorting mechanism is in operation.

Secured to the shaft 74 is a series of surfaced ribbed rollers 79. Carried in bearings above shaft 74 is a second shaft 80, this shaft being driven from the shaft 74 by the gearing 80a. Mounted on the shaft 80 and secured to it by set screws, is a series of disc members 81 (Figs. 6 and 8), four in number and of identical constructions. The disc members 81 have a portion of their periphery turned down to form a flange 82. At four equidistant points around the periphery of the discs 81 are bored recesses 83, these recesses extending almost to a large central bore 84 in the disc 81, and being connected to the said central bore by the holes 85, which are of lesser diameter than the recesses 83. Mounted within the recesses 83 are the cup-shaped plungers 86, these plungers having at one side the slots 87. Mounted within the bore of the cup plungers 86 are the pin plungers 88, whose lower ends terminate in a tooth portion 90, the reduced portions 89 of the pin plungers projecting into the holes 85 on the central bore of the disc 81. The pin plungers 88 have projecting from one side the stop pins 91. These stop pins pass through the slots 87 in the cup plungers and through the slots 92 in the side of the discs 81, and serve to limit the outward travel of the plungers. Within the cup plungers 86 and bearing on the top of the pin plungers 88, are the springs 93. Mounted in the holes 83 below the cup plungers, are the springs 94, which bear against the lower edge of the cup plungers 86, and have a lesser modulus than the springs 93. Loosely mounted on the shaft 80 and within the central bore 84, is a ratchet wheel 95 having a central loose bushing. Extending to the left, and integral with the ratchet wheel 95, is a hub terminating in a bevel gear 96.

Mounted within the flanged portion 82 of the disc, and bearing on the ends of the cup plungers 86, is a rim member 98, whose outer surface is knurled or otherwise roughened. The rim member 98 and the ratchet wheel 95 are held in position on the disc 81 by a side plate 99, secured to the disc by the screws 100. Within the body of disc 81 is a slot 101 for the reception of a pin 102 which projects inwardly from the rim member 98 and provides driving connection to the floating rim members as the disc 81 is rotated.

Operation of the coin unit mechanisms

As the coins are delivered to the coin delivery chutes 71 by the coin conveyor delivery chain,

they assume a flat position due to the method of delivery by the coin conveyor chain, as has been described, and present themselves in the position shown by the dotted lines at 103 in Figure 7, to the pinch of the rolls 79 and the floating rim members 98, and are drawn between the rolls and the rim members. If the coin be a thin one, the respective rim member 98 is deflected inwardly the minimum amount, one of the cup plunger springs 94 yielding to permit the rim member to move at that particular point. Coincidentally with the moving of a cup plunger 86, its pin plunger moves upward, due to the excess pressure of the spring 93 over that of the spring 94, and the toothed end 90 of the pin plunger engages the ratchet wheel 95, moving it forward as the rotating disc turns, a distance appropriate to the denominational value of the coin passing the pinch of rolls 79 and rim member 98. The action, as described, is presumed to have occurred when one of the plunger units was in direct line with the coin passing between the roll and rim member. Now, if the coin arrives at the pinch of the roll and rim member at a point midway between the two plunger units, the effect will be to depress both units and engage two of the toothed ends 90 of the plunger units with the ratchet wheel 95, advancing it the same distance as one of the plunger units would, if one only was engaged.

So far the description has been based on a coin of minimum thickness, and, since the mechanism must be able to accept coins of a maximum thickness, such as new coins, it follows that provision must be made for the passage of coins through the rolls and rims, from the thinnest to the thickest coin.

In order that a thick coin may pass through the mechanisms, the compound plunger system heretofore described is used. If but a single plunger 88 were used, when the rim member had pressed the toothed end of a plunger into contact with the ratchet wheel 95 under the influence of a thin coin, no further movement of the rim member would be possible. With the construction shown, however, if a maximum movement of the floating rim members is called for, the first movement of the floating rim member 98 compresses the springs 94 until the toothed portion 90 of a pin plunger 88 is stopped by contact with the ratchet wheel. By then, as the cupped plungers 86 compress the spring 94 still further, and at the same time compress the stronger spring 93, the cupped plungers slide past the now stationary pin plungers 88 and thus permit the floating rim members to have the maximum of movement necessary to permit a thick coin to pass through the unit count mechanisms.

As the coins pass between the rolls 79 and the floating rim members 98, the engagement of the toothed end of the plungers 88 gives the ratchet wheels 95 and the bevel gears 96 a degree of advance proportionate to the value of the coin passing through. The purpose of this step by step advance of the bevel gears 96 will be described later in connection with the description of a totalling unit count assembly.

After the coins pass the coin unit count assembly, they pass down the coin chutes 104 and are deposited in the bags 106, secured to the bag holders 105, by a clip or other fastening device 107.

The half-dollar unit count mechanism

Formed on the right hand end of the coin plate 4 (Figs. 3 and 5) is a bracket 108. De-

pending from the bracket 108 is a bearing bracket 109 which supports a shaft 110, the outer end of which is secured to a bevel gear 111 which is in driving relationship with a bevel gear 112 on the driving disc 14. Secured on the opposite end of the driving shaft 110 is a coin count wheel 113 which has a flanged periphery. Between the flanges, on the flat portion of the periphery of the wheel 113, is a series of recesses 114 (Fig. 21) which have a smaller diameter hole at their bases. In the outer or left hand flange (as seen in Fig. 18) of the coin count wheel 113 is a series of slots 115. Mounted in the recesses 114 of the count wheel 113, is a series of plungers having reduced diameters, to form the stems 117, around which are mounted the springs 118, which are seated in the bases of recesses 114. The stems 117 project into and are guided by the smaller diameter holes of the wheel. The plungers 116 have in their side walls the pins 119 which project through the slots 115 in the count wheel 113, and extend outwardly beyond the face of the count wheel. The shaft 110 extends to only near the center of the count wheel 113.

25 The bracket 108 has a bearing for a shaft 120, which has on its outer or left hand end a bevel gear 121, its inner or right hand end extending into, and having a bearing in, a central hole in the count wheel 113. Mounted on the shaft 120 and pinned thereto, is a hub 122, which has on its right hand end a ratchet disc 123 (Fig. 20), and on its left hand end a serrated locating stop disc 124. Mounted on a pivot above the serrated disc is a detent arm 125, the inner end of which is shaped to fit the serrations of the disc 124, and which is held in yielding engagement with the stop disc 124 by means of a spring 126.

The coin count wheel 113 is driven in timed relationship with the traveling coin conveyor chain, by the bevel gears 111 and 112, and the plungers 116 thus synchronously strike the center portion of the coin holes 22a of the coin conveyor chain 30. If a half-dollar coin be present in a coin hole of the coin conveyor chain, then a plunger 116 at the lower portion of disc 113 is depressed and the pin 119 moves into the path of a tooth of a ratchet disc 123 and advances it one step forward, the detent arm 125 riding over one serration of the disc 124. As a plunger leaves the coin, it returns to normal position, freeing the pins 119 from the ratchet. If a thin coin be present in a coin hole 22a of the coin conveyor chain, the pin 119 may carry the ratchet slightly less than the correct distance. Or, if a thick coin, it may carry the ratchet slightly beyond the proper distance. The serrated disc 124, however, will, by reason of the shape of its serrations and the detent arm 125, correct the error as the pin 119 releases the detent ratchet.

60 The bracket 108 at the left (Fig. 5) is extended downwardly and outwardly to form two bearing brackets 127, in which is mounted the shaft 128. The upper end of this shaft extends above the upper bearing bracket 127, and has secured to it the bevel gear 129; and the lower end of the shaft extends below the lower bearing bracket and has secured to it the bevel gear 130. The shaft 128 and its gears are driven from the bevel gear 121, whenever that gear is motivated by a half-dollar coin passing the coin unit count wheel 113.

After a half-dollar coin has passed the count wheel 113, it is carried by the coin conveyor chain until its upper edge reaches the end of the ledge 70, when it falls by gravity into a coin chute 131, and is deposited in its coin bag, as has been set

forth in the description of the disposal of coins of lesser value.

Coin unit totaling counters

The coin unit counters are arranged to drive a series of coin unit totaling counters, one for each coin value to be counted, and an inspection of Figures 6 and 7 shows that each of the coin unit counters drives a bevel gear 96, which is in driving contact with a similar bevel gear of one of the coin unit totaling counters, as will be presently set forth.

By means of these coin unit totaling counters, it is possible for the operator of the machine to have a totalized denominational value in dollars and cents of each sack of coins. The mechanisms for accomplishing this result will now be described.

A rectangular frame member 133 is supported by two brackets 134, which extend upward from the coin plate 4 and support the said frame in a position to the left of the coin unit count assembly, as is seen in Figure 7. The end members of this frame 133 are grooved as at 135. Mounted within the frame is a second or inner slidable frame 137, the end members of which have a projecting rib 138 which engages the groove 135, slidably supporting the inner frame at its two ends. The bottom of the outer frame has secured to it a series of cross bars 139. Each of these cross bars 139 carries, at a suitable position, a supporting bracket 140. These brackets extend upwardly inside of the movable frame 137, and have in their free ends a hole 141. The round bars 142 are seated in the front side wall (Fig. 27) of the frame 133, and their other ends are seated in the supporting brackets 140 and project beyond these supporting brackets about one-fourth of an inch. The projecting ends of the round bars 142 furnish bearings for certain parts of the mechanisms which will be explained later.

Mounted on the round bars 142 are indicating wheel assemblies 143, free to revolve, and held in spaced relationship by the necessary spacing collars. These indicating wheel assemblies (Figs. 27-30) consist of an indicating wheel 143, a setback gear 145, a wide gear wheel 146, and a transfer disc 156. The final or last indicating assembly has no transfer disc 156. The indicating indicia on the wheel assemblies 143 are from 0 to 9.

There are five groups of these indicating wheel assemblies, as follows: three assemblies for the half-dollar counting group, which is to the left (Fig. 27) in the sliding frame 137; three assemblies for the next to the left, or quarter counting group; four in the next or nickel counting group; four in the next or penny group; and three in the extreme left or dime group.

A series of shafts 148 pass through the outer stationary frame 133 and have a bearing in the frame, and then pass loosely through a sliding frame 137 and are aligned with the round bars 142. The shafts 148 extend outside of the frame 133 (Fig. 7), and have bevel gears 149 secured to them, these gears being in driving relationship with the gears 96 of the coin unit count mechanism. Secured to shafts 148 and outside of the frame 133, are the serrated ratchet wheels 150, each with its retention pawl 151 and pawl retent spring 152.

Secured to the cross bars 139 are the brackets 153, one being located at the left of the frames at the half-dollar totaling position, the second one being located at the right hand end of the frames, in line with the dime totaling position.

The left hand bracket 153 has fastened to it a

non-rotary disc 154 which has a single indicium, this indicium being the figure 0. In its center, the disc 154 has an opening for the passage of one of the shafts 148. The inner end of shaft 148 has secured to it an indicating figure wheel 155. On the face of this wheel are the indicia 0 and 5 repeated five times around its periphery. Fastened to the lower face of the indicating figure wheel 155, is a five point transfer disc 156 (shown in Fig. 32), and on the upper face of indicating figure wheel 155 is a set-back gear 145. The lower face of the indicating wheel 155 has a central hole which forms a bearing for the indicating wheel on the extending end of the round bar 142.

15 Mounted in the sliding frame 137 is a shaft 157. Running free on this shaft, are the transfer hubs 158, having on their right hand end (Fig. 30) a disc 159, this disc carrying on its right hand face a series of five transfer pins 160, adapted, in one position of the sliding frame 137, to lie in the path of a transfer disc 156 of one of the indicating wheel assemblies 143, and in another position of the sliding frame 137, to be free of the transfer disc 156. To the left on the transfer hub 158 is a narrow gear 161 in driving engagement with the wide gear wheel 146 of one of the indicating wheel assemblies 143. By this arrangement the gear 161 is at all times in driving engagement with the gear 146, irrespective of the shifting of the sliding frame 137 to the right or left.

30 Mounted in the inner frame 137, at a point to the rear of the indicating wheel assemblies, are the shafts 162 (Figs. 29 and 30), these shafts having securely mounted on them the detent arms 163. The outer ends of these detent arms bear against the transfer pins 160, and serve as a position stop therefor. To the rear of the shaft 162 is a rod 162a having secured to it the springs 164 which are fastened to an extension 165 on detent arm 163. The construction described permits of the yielding of the detent arms as the transfer pins are moved.

45 So far most of the description of the parts of the totaling unit count mechanism has been directed to the left hand or half-dollar counter. As has already been stated, all the indicating wheel assemblies below the brackets 140 (Fig. 27) are of identical construction, and further consideration of their parts is unnecessary.

50 First, the operation of the half-dollar total count will be described, to the point where it picks up the indicating wheel assemblies, it being understood that when the indicating wheel assemblies 143 are picked up, their further operations are but a series of repetitions. Following the description of the half-dollar total count, the quarter, five cent, penny and dime total counts will be taken up in the above order, and their differences pointed out. The set-back or zero return for the totaling unit counters will be taken up later.

55 Presume now, that there is a supply of coins in the coin hopper, and consider, for the time being, the half-dollars only. As the coin conveyor chain moves in a clockwise direction, it picks up coins in the coin holes 22a, and the half-dollars are carried on and pass under the unit count disc 113, depressing the plungers 116 thereof, thus setting into motion the ratchet 123, the shaft 120, the gears 121 and 129, the shaft 128, the gears 130 and 149, the shaft 148, and the indicating wheel 155 in the totaling unit count frame. All of these mechanisms are advanced 70 one-tenth of a revolution as each half-dollar

passes beneath the unit count disc 113. If there be no half-dollar present in the coin holes 22a of the coin conveyor chain, the count plungers are not depressed, and there is no count.

5 When the first coin passes under the unit count disc 113, the indicating wheel 155 being advanced one-tenth of a revolution, and the fixed indicium disc 154 showing 0, the reading will now be 50, showing fifty cents as having been recorded. As the second coin passes under the unit disc 113, the indicating wheel 155 is again advanced one-tenth, and now shows 0. Since the indicating wheel 155 carries a five point transfer disc 156 (Fig. 32), the first indicating wheel assembly is picked up by one of the points 166 of the transfer disc 156 striking a pin of the transfer assembly 167, and advancing it one pin. The gear 161 of the transfer assembly advances the gear 146 of the indicating wheel assembly one-tenth, and shows the figure 1 on that wheel, the total reading now being 100, or one dollar. The continued advance by tenths of the mechanism will show next 150, 200, etc., until all the half-dollar coins carried by the coin conveyor chain 30 have been counted.

The quarter mechanism

35 The first indicating wheel 168 of the quarter totaling counter differ from the half-dollar in that there is no fixed unit carrying the figure 0. Instead, there are two count wheels 169 and 170 mounted on a common hub and turning in unison, driven by the gear 96 on the unit count wheel assembly and the gear 172 on the shaft 148. The right hand count wheel 170 (Fig. 30) has 40 to its right a set-back gear 145, and the left hand count wheel has a two point transfer disc 156 (Fig. 33) secured to its left face. The right hand indicating wheel has indicia showing 0—5—0—5 etc. on its face, and the left hand wheel has 0—2—5—7—and repeat. As the coins are dropped by the coin conveyor chain and pass through the unit count disc 98 of the unit count assembly, the quarter totaling unit counter showing 0—0 on the two count wheels 169 and 170, moves 45 one-eighth of a revolution (since all the mechanisms pertaining to the quarter distribution and count are operated in eighths). The indicating figures of the two count wheels 169 and 170 show, on the first movement, 25, on the second movement 50, on the third movement 75, and on the fourth movement 00. When this fourth movement occurs, one of the points 166 on the two point transfer wheel moves a pin of the transfer assembly 167, and one of the indicating wheel assemblies 143 is advanced one-tenth, showing 1, and the totaling count now shows 100. The fifth movement shows 125, the sixth 150, the seventh 175, and on the eighth movement the second point on the transfer disc moves the indicating wheel assembly a second tenth, the reading now being 200. The reading thus proceeds to its end 55 in the above progression.

The five cent mechanism

60 There is but one indicating figure wheel 171 (Fig. 27) for the five cent counter, this wheel showing 0—5—0—5—0, and repeat, around the wheel face. The indicating figure wheel has secured on its upper face a set-back gear wheel 145, 70 and on its lower face a five point pick up disc 156. As the indicating figure wheel 171 is moved one tenth by the unit count mechanism, the gear 96 and gear 173 on the shaft 148, the first movement from 0 shows 5. The second movement of 75

indicating figure wheel shows the 0 again, but the five point transfer disc has advanced the first wheel of the indicating wheel assembly 143 one-tenth, so that the reading of the indicia of the two wheels is 10. On the third movement the reading is 15, on the fourth, 20, and in like progression until all the coins of a five cent value in the coin conveyor chain 30 are disposed of.

The penny mechanism

The penny first indicating figure wheel 174 is like that of the five cent mechanism, being the only wheel on the shaft 148, and having the set-back gear 145 secured to its upper side, and a single point pick up disc 156 (Fig. 31) on its lower side. The indicia on its face run from 0 to 9. The tenth movement of the first indicating figure wheel 174 picks up the first wheel of the indicating wheel assembly 143, and the reading is than 1 on the indicating wheel assembly 143, and 0 on the penny indicating wheel 174, the total reading being 10. As the penny indicating wheel 174 continues to turn in tenths under the influence of the coins passing the unit count disc 98, the wheels will show 11, 12, etc., until the second tenth is completed by the first wheel. When the indicating assembly wheel makes its second one-tenth movement, 20 will show as a reading, and so, until all the coins of a penny value in the coin conveyor chain 30 are disposed of.

The dime mechanism

The dime count mechanism has at the top a fixed figure disc 175 similar to that of the half-dollar. The dime indicating wheel 176 is marked from 0 to 9. It has the usual set-back gear to the right, and a single pick up point disc 156 to the left. As the indicating wheel 176 advances by the movement of the coins in the coin conveyor chain dropping past the unit count disc 98, the first reading after 0-0 will be 10, the second 20, and so on until the tenth movement again shows 0-0 for these two wheels. When the dime indicating wheel 176 again passes to 0, the single point pick up disc advances the first unit wheel of the indicating wheel assembly 143, one-tenth, so that the reading is then 100. This routine continues until all of the coins of a dime value in the coin conveyor chain 30 have been counted.

All of the coins placed in the hopper 33 having been counted, their totals are shown by the totaling unit count wheels, and the counting mechanisms are ready to set to zero. This will now be described.

The totaling counter set-back mechanism

It is to be presumed that in the counting operations just set forth, the sliding frame 137 was in the position shown in Figure 27, that is, at the top. With the frame 137 in this position, the pins of the transfer mechanisms 167 were all in line with the transfer discs 147 on the various indicating figure wheels.

Since these pins would prevent the indicating wheels from reverse movement, they must be moved out of line with the transfer discs 147. As the carrying shafts of these transfer mechanisms are mounted in the sliding frame 137, any movement of this frame downward (Fig. 27) will carry the transfer mechanisms 167 and the pins 160 free of the paths of the transfer discs 147.

Mounted on the side of the stationary frame 133, by means of the studs 177, is a sliding rack bar 178. This bar has slots 179 to permit of the movement of the bar, and the rear face of the

bar has a series of rack teeth 180 along the entire length of the bar. Secured to the outer surface of the sliding bar is a cam member 181 (Figs. 27, 28, 30) having a tapered face 182. A second cam member 183 is fastened to the sliding bar, and has a tapered end 184. These cam members are so disposed as to leave a space on the track 185 between the two tapered faces.

Secured in the sliding frame 137 is a stud 186. This stud projects through an opening in the stationary frame 133, and has a pin 187 which projects in the path of the face of the cam members 181 and 183. An inspection of Figure 30 shows that if the rack bar be moved downward, the pin 187 will reach the track 185 and be forced to the right by the tapered face 182 of the cam member 181. This movement to the right of the stud 186 moves the sliding frame 137 to the right, moving the transfer mechanism 167 to the right into engaging position with the transfer discs 147 on all of the counting wheels. This is the position shown in Figure 21. It follows, then, that any movement upward of the rack bar 178 will pull the sliding frame to the left, to the position shown in Figure 30, putting the counting wheels in a position to be re-set. A total movement of the rack bar of less than one-eighth inch is needed to effect this movement of the frame.

Mounted in bearings in the fixed frame 133 is a series of five shafts 188, these shafts passing through holes in the sliding frame 137 and being free to rotate therein. On the left end, these shafts have secured to them the gears 189, which are in engagement with the teeth on the rack bar 178. The left hand shaft 188 is longer than the others of the series, and has mounted on it the handle 190 for manual turning.

As has been stated, each of the indicating count wheel assemblies 143 has incorporated with it a set-back gear wheel 145 with two of its teeth cut away (Fig. 29). Mounted on the shafts 188 and pinned thereto in line with the set-back gears 145, is a series of gear wheels 191, each having a blank space 192 equivalent to two teeth (Fig. 29).

In order that an understanding of the set-back mechanisms may be had, a description of one of the totaling unit counters (the five cent) will now be given, it being understood that the other units operate in a like manner.

With the five cent count mechanism in the position shown in Figure 27, the indicating wheel 143 will show 0. If now the count wheel 176 be advanced in the direction of the arrow one-tenth of a revolution by one of the points of the five point transfer disc 156, the set-back gear 145 will be advanced one tooth, the tooth passing the cut away space 192 in the gear member 191. If now the handle 190 on the shaft 188 be operated to move the rack bar in the direction of arrow X (Fig. 28), the initial movement of the rack bar will slide the frame 137 to the left (as seen in Fig. 30), releasing the pins 160 from the path of the transfer disc 156, the toothless space on the gear member 191 permitting this initial movement of the rack bar without the teeth of the toothed member 191 striking the tooth of a set-back gear before the counting wheels are released from the transfer assembly 167. The further movement of the rack bar 178 continues the movement of the toothed wheel 191 in the direction of the arrow, the first tooth of this member 191 striking the advanced tooth of the set-back gear 145 on the count wheels, and moving it until the cut-out space is reached, the indicia of the count wheel then showing 0. In the

further movement of the gear wheel 191, the remaining teeth of that wheel pass without effect across the toothless space of the set-back gear 145. If the set-back gear had several teeth advanced, they are picked up by the toothed member 191, one by one, until the blank space is reached. It is thus seen that no matter how many teeth of a given set-back gear wheel are advanced, the count assemblies are always returned to zero by 10 a full movement of the rack bar.

In the rapid operation of the count mechanism, the action of the transfer points 156 in striking the transfer pins 160, would tend to spin the count indicating wheels, and it becomes necessary, 15 therefore, to provide a braking action for these count wheels. An inspection of Figure 29 shows that one of the transfer pins 160 is always in rubbing contact with the circular face 193 of the transfer disc 156, and exerts a braking action 20 thereon. The count wheels are thus prevented from any spinning action.

Defective or bent coin disposal

Coins that are mutilated or bent will not remain in the coin spaces of the coin conveyor chain 30, either jumping out of their own accord, or being dislodged by the flexible dam 47, and are caused to accumulate at a point near the lower left hand corner (Fig. 3) of the coin plate, 30 on account of the speed of the coin conveyor chain 30 and the angle of inclination of the coin plate 4. Attention is now called to the coin deflector 44 (Figs. 3-17), and to the rear lower edge thereof. This lower edge rests on a movable dam member 35 193 which closes a slot 194 in the wall 20. A guide 195 is secured to the closure member 193 and extends upward a distance above the wall 20 and has an operating handle 196. A limit pin 197 projects through a slot 204 in the wall 20, and is 40 secured in the guide member 195. This limit pin has a spring 198 which keeps the closure member seated at all times, and thus closes the slot 194.

When the perfect coins have been disposed of, the coin conveyor chain 30 is permitted to run, 45 and the handle of the closure member 193 is lifted. The centrifugal force of the coin conveyor chain quickly discharges the defective coins through the slot 194 into a proper receiving receptacle, such as a drawer 199 (Fig. 1), from 50 which they can be recovered.

Power to drive the mechanisms may be furnished by a motor or other power unit 200 (Fig. 1) driving a belt 201 which passes over the pulley of the combined pulley and flywheel 7 (Fig. 4). 55 The operations of the mechanisms may be observed at all times through a glass inspection door 202 in the top of the housing of the machine, and the totalized count of the coins may be easily read through the inspection holes 203.

Having fully set forth my invention, what I claim as new and desire to secure by Letters Patent, is:

1. In a coin machine, a coin sorting mechanism comprising an elongated coin plate with 65 semi-circular ends set at an angle transversely of its length, a driven chain running around the margin thereof, each link of the said chain forming a carrier for a single coin of any denomination, and means at the upper edge of the said 70 plate to allow the coins to be dropped from their respective links at various stations according to their denominations, and means to enforce the dropping of the coins at their respective stations.

2. In a coin machine, a coin sorting mechanism comprising an elongated coin plate with 75

semi-circular ends set at an angle transversely of its length, a driven chain running around the margin thereof, each link of the said chain forming a carrier for a single coin of any denomination, and means at the upper edge of the said plate to allow the coins to be dropped from their respective links at various stations according to their denominations, said means comprising a slot underneath the chain, of increasingly greater width in the direction of motion of the said chain, 10 the first width being such as to allow only the smallest coin to pass through, and the last being such as to permit the largest coin to pass through, there being an intermediate width for every intermediate size of coin, and means to enforce 15 the dropping of the coins at their respective stations.

3. In a coin machine, a chain to carry the coins from their point of deposit in the machine to a sorting device, said chain comprising a series of coin carrying links, each link having a hole therein of sufficient size to substantially seat any coin, and means to prevent more than one coin of any denomination to be seated therein and carried thereby at one time, said means comprising 25 an abutment cutting off enough of the area of the hole, so as to permit a substantial part of the largest coin to be seated therein, and yet to prevent more than one of the smallest coins to lie flat therein. 30

4. In a coin machine, a chain to carry the coins from their point of deposit in the machine to a sorting device, said chain comprising a series of coin carrying links having chamfered portions, each link having a hole therein of sufficient size to substantially seat any coin, and means to prevent more than one coin of any denomination to be seated therein and carried thereby at one time, said means comprising an abutment in the region of said chamfered portion cutting off enough of the area of the hole, so as to permit a substantial part of the largest coin to be seated therein, and yet to prevent more than one of the smallest coins to lie flat therein, said means comprising, in addition, a deflector 45 dam resiliently held against the said chain, and free to rise only a sufficient amount to pass a partially seated large coin, while brushing off over said chamfered portion any coins resting on top of an already seated coin. 50

5. In a coin machine, a chain to carry the coins from their point of deposit in the machine to a sorting device, said chain comprising a series of coin carrying links, each link having a hole therein of sufficient size to substantially seat any coin, and means to prevent more than one coin of any denomination to be seated therein and carried thereby at one time, and means driven in timed relation to said chain to insure that each coin is seated to the fullest extent possible 55 in its link before it reaches the sorting device. 60

6. In a coin machine, a chain to carry the coins from their point of deposit in the machine to a sorting device, said chain comprising a series of coin carrying links, each link having a hole therein of sufficient size to substantially seat any coin, and means to prevent more than one coin of any denomination to be seated therein and carried thereby at one time, and means to insure that each coin is seated to the fullest extent possible 70 in its link before it reaches the sorting device, said means comprising a seating disc having radial spring plungers around its periphery, and driven in a plane transversely to the path of 75

the chain in synchronism with the said chain, so that one spring plunger presses upon the coin in each link as it passes.

7. In a coin machine, a coin sorting mechanism comprising an elongated coin plate with semi-circular ends set at an angle transversely of its length, a driven chain running around the periphery thereof, each link of the said chain forming a carrier for one coin of any denomination, 5 and means at the upper edge of the said plate to cause the coins to be dropped from their respective links at various stations according to their denominations, said means comprising a slot underneath the chain, of increasingly greater 10 width in the direction of motion of the said chain, the first width being such as to allow only the smallest coin to pass through, and the last being such as to permit the largest coin to pass through, there being an intermediate width for 15 every intermediate size of coin, said means com- 20

prising in addition, a series of discs, one for each station, having radial spring plungers around their peripheries and driven in synchronism with the said chain so that one spring plunger presses upon the coin, if one be present, as its link carries it opposite each of the aforesaid stations, whereby the said coin is positively forced through the slot which is just wide enough to accommodate it. 5

8. A coin sorting machine having an endless coin conveyor chain running in a curved path, on a coin table in a plane at an angle to the horizontal, and having means to reject bent or mutilated coins, and closure means in said table, located at the point at which said rejected coins 15 collect by virtue of the movement of the chain and the inclination of the table, whereby said defective coins are discharged upon opening said closure. 10

EDWARD B. PAUL. 20
